UNITED STATES PATENT OFFICE.

HERMAN H. MELAUN, OF INDIANAPOLIS, INDIANA.

DESIGN FOR AN ELECTRICAL LIGHTING FIXTURE.

Application filed March 23, 1928. Serial No. 25,972. Term of patent 3½ years.

To all whom it may concern:

Be it known that I, HERMAN H. MELAUN, a citizen of the United States, residing at Indianapolis, in the county of Marion and State of Indiana, have invented a new, original, and ornamental Design for Electrical Lighting Fixture, of which the following is a specification, reference being had to the accompanying drawings, forming a part thereof.

In the drawings, Fig. 1 is a top plan view of the electrical lighting fixture. Fig. 2 is a side elevation thereof.

I claim:

The ornamental design for an electrical lighting fixture, as shown.

HERMAN H. MELAUN.
